United States Patent Office

Des. 185,309
Patented May 26, 1959

185,309

MATERNITY SUPPORTER

Beverly L. Norman, Houston, Tex.

Application June 17, 1957, Serial No. 46,611

Term of patent 14 years

(Cl. D20—2)

Fig. 1 is a front perspective view of a maternity supporter embodying my new design;

Fig. 2 is a side perspective view; and

Fig. 3 is a rear perspective view.

I claim:

The ornamental design for a maternity supporter, as shown.
